Primary Examiner—Louis S. Zarfas*Assistant Examiner*—I. Simmons*Attorney, Agent, or Firm*—Knobbe, Martens, Olson & Bear[57] **CLAIM**

The ornamental design for an infusion pump, as shown and described.

DESCRIPTION

FIG. 1 is a top perspective view of the infusion pump of the present invention;

FIG. 2 is a bottom perspective view of the infusion pump of the present invention;

FIG. 3 is a top elevational view of the infusion pump of the present invention;

FIG. 4 is a bottom elevational view of the infusion pump of the present invention;

FIG. 5 is a side elevational view of the infusion pump of the present invention; and,

FIG. 6 is a side elevational view of the infusion pump of the present invention, rotated ninety degrees on its axis relative to FIG. 5.
